UNITED STATES PATENT OFFICE.

JOSEPH R. LOCKE, OF AMESBURY, MASSACHUSETTS.

DESIGN FOR CARRIAGE-WHEEL HUBS.

Specification forming part of Design No. 6,997, dated November 18, 1873; application filed August 27, 1873.
[Term of Patent 7 years.]

To all whom it may concern:

Be it known that I, JOSEPH R. LOCKE, of Amesbury, of the county of Essex and State of Massachusetts, have invented a new and useful and Ornamental Design for the Hub of a Carriage-Wheel; and do hereby declare the same to be fully described in the following specification and represented in the accompanying drawings, of which—

Figure 1 is a side view, and Fig. 2 a front elevation, and Fig. 3 a transverse section, of a cast-metal hub provided with the said design, which consists in forming each collar of the hub with a series of semi-globular or convex bosses, arranged at equal distances apart around the collar, the said collar being formed in other respects as shown.

In the drawings the hub is shown as consisting of two tapering annuli or collars, A A', arranged with their bases at short distances

asunder, and parallel and connected by a series of radial wings, B, also arranged at equal distances apart, all as represented.

In carrying out my design, I not only form the outer surface of each of the collars A A' in manner, or of the hat shape, as represented, but also with a series of bosses, or spherical or convex projections, a a a, formed and disposed as shown.

What I claim is—

The ornamental design for hub-collar, essentially as represented, such including the series of semi-spherical bosses and the hat-shaped surface from which they project, all as set forth.

JOSEPH R. LOCKE.
